UNITED STATES PATENT OFFICE.

NORBERT V. WINTER, OF LOS ANGELES, CALIFORNIA.

DESIGN FOR A TOY COUCH.

Application filed January 30, 1926. Serial No. 16,335. Term of patent 14 years.

To all whom it may concern:

Be it known that I, NORBERT V. WINTER, a citizen of United States, residing at Los Angeles, in the county of Los Angeles and State of California, have invented a new, original and ornamental Design for a Toy Couch, of which the following is a specification, reference being had to the accompanying drawing, forming part thereof.

The figure is a perspective view of a toy couch, showing my new design.

I claim:

The ornamental design for a toy couch, as shown.

In testimony whereof I affix my signature.

NORBERT V. WINTER.
